UNITED STATES PATENT OFFICE

122,713

DESIGN FOR A BOTTLE

Alfred Munzer, New York, N. Y., assignor to
Barcelo, Marques & Co., S. en C., Arecibo,
Puerto Rico

Application August 1, 1940, Serial No. 94,123

Term of patent 14 years

To all whom it may concern:

Be it known that I, Alfred Munzer, a citizen of the United States of America, residing in the city of New York, county of New York, and State of New York, have invented a new, original, and ornamental Design for a Bottle, of which the following is a specification, reference being had to the accompanying drawing, forming part thereof.

I claim:

The ornamental design for a bottle, as shown.

ALFRED MUNZER.
